UNITED STATES PATENT OFFICE.

ARTHUR FREDERICK PYM, OF MARBLEHEAD, MASSACHUSETTS, ASSIGNOR TO UNITED SHOE MACHINERY CORPORATION, OF PATERSON, NEW JERSEY, A CORPORATION OF NEW JERSEY.

WORK-POSITIONING MEANS.

Application filed January 9, 1925. Serial No. 1,485.

This invention relates to work positioning means for use in the manufacture of boots and shoes, and in different aspects has in view the provision of means for positioning 5 insoles on their lasts and means for positioning lasts and their shoe materials relative to means for operating on said materials.

It has been the general practice heretofore 10 in the manufacture of welt and other types of shoes to fasten the insole to its last by tacks driven usually at the toe and heel ends and in the shank. There are, however, well known objections to the use of such 15 tacks. It sometimes happens, for example, that a tack is left in the insole until the shoe is finished, and such a tack not only may cause injury to the wearer of the shoe but is very difficult to remove without damage 20 to the shoe. Since, moreover, the tacks are driven in about the same locations in the manufacture of different shoes on the same last, the wood of the last may finally become so disintegrated that the tacks no longer 25 hold effectively. Furthermore, in the prevailing practice the accuracy with which the insole is positioned on the last depends entirely upon the operator's care and judgment.

30 In view of the foregoing, the present invention, in one important aspect, provides novel means for positioning and holding insoles accurately in predetermined relation to their lasts without the use of tacks. The 35 construction shown comprises a spring-metal clamping member applied to the bottom face of the insole and extending along the fore-part and rearwardly also along the shank. This member is shaped to hold the insole 40 in close conformity to the shank curvature of the last, and is attached to the last by means of a pin projecting through a hole in the insole into a hole or socket formed in the bottom of the last. To adapt it to apply 45 effective clamping pressure to the insole, the clamping member herein shown is so shaped as to be subjected to bending stress in forcing it into clamped position, and when it has been thus applied its resiliency is utilized for 50 holding it in clamping position by cramping the pin in the hole in the last. It will be understood that the last will be provided

with a hole in its bottom portion in predetermined relation to its edge contour to receive the pin, and that the insole will be 55 provided with a hole in corresponding relation to its edge contour so as to register with the hole in the last when the insole is in proper position on the last. The pin accordingly serves to locate the insole in the 60 proper position and is held in place by the cramping action of the clamping member.

As herein shown, holes such as above mentioned are located in the toe end portions of the last and the insole, and it is contemplated that a single clamping member provided with a pin to enter such holes will be sufficient for positioning and holding the insole in most lines of work, since the lengthwise and lateral position of the toe end of 70 the insole will thus be accurately determined, it being understood that when the insole has been properly positioned it is held effectively from turning movement by the pressure of the clamping member. If desired, 75 however, an additional positioning or clamping device cooperating with holes similarly formed in the heel end portion of the last and the insole may be provided, as also herein shown to insure absolute accuracy as 80 to the lateral position of the heel end of the insole.

It is a further object of the invention to provide means for positioning a last and its shoe materials relatively to means for operating on said materials, and in one important aspect to provide means for carrying out the method set forth in my prior application Serial No. 698,099, filed on March 10, 1924, when the insole positioning means of 85 this invention is utilized. In accordance with the disclosure of said prior application, the last and its shoe materials are positioned in predetermined relation to means for operating on said materials, for example to toe-embracing wipers, by mounting the last on an axis bearing a definitely predetermined relation both to the contour of the last and to the wipers, the last and the insole being provided with registering holes in predetermined relation to their contours, substantially like the holes herein shown as adapted to receive the clamp-positioning pin, and the lasting machine having a pin located in 90 95 100

correspondingly predetermined relation to the edges of the wipers to enter said holes. For purposes of the present invention the insole positioning or clamping device is provided with means for use in positioning the last and its shoe materials. More particularly, in the construction herein shown the forepart and shank clamping device is provided with an outwardly projecting pin 10 which is coaxial with the pin that enters the hole in the last and thus bears a definitely predetermined relation to the contour of the last, and the machine is provided with a socket bearing correspondingly predetermined relation to the edges of the wipers to receive the outwardly projecting pin. It will thus be seen that the last is mounted on an axis bearing a definitely predetermined relation both to its contour and to the wipers 20 in accordance with the method of the earlier application.

The invention will now be more particularly described by reference to the accompanying drawings and thereafter pointed 25 out in the claims.

In the drawings:

Fig. 1 shows a last and an insole with insole positioning means provided by the present invention, a clamping device being applied at the heel end and a forepart and shank clamping device shown detached; this figure showing also a part of a shoe machine formed to cooperate with the insole clamping means to position the last;

Fig. 2 is a plan view of the forepart and shank clamping device;

Fig. 3 illustrates more fully the use of the clamping device shown in Fig. 2;

Fig. 4 shows in front elevation a portion 40 of a toe lasting machine having means for positioning the last and its shoe materials in accordance with the method of my prior application when the insole clamping device of Fig. 2 is utilized; and

Fig. 5 is a plan view of the parts shown in Fig. 4.

For purposes of the present invention, in its illustrated embodiment, there is provided a spring-metal clamping member 2 adapted 50 to be applied on the bottom face of the insole α and to extend along the forepart and rearwardly over a portion of the shank. This member may be differently shaped, as desired, to overlie more or less of the width 55 of the insole, the construction shown comprising a comparatively narrow plate adapted to extend lengthwise of the insole substantially midway between the opposite sides of the last. The rear end portion of the 60 member 2 is bent relatively to the front portion so as to engage the shank portion of the insole with effective clamping pressure and to hold it in close conformity to the shank curvature of the last. As shown by dotted 65 lines in Fig. 3, the member 2 has normally a

sharper curvature than the corresponding portion of the bottom of the last, thereby adapting it to be sprung into clamping position by pressure applied between its opposite end portions.

For attaching the clamping member 2 to the last and for holding it in clamping position a pin 4 is provided, this pin in the construction shown being fast on the clamping member. To receive the pin 4 the last 70 is provided in the bottom of its forepart with a hole or socket 6, a metal bushing 8 being inserted to prevent undue wear. The insole likewise is provided with a hole 10 so located as to register with the hole 6 in the last when the insole is in its proper position on the last. By reference to Fig. 3 it will be seen that the normal curvature of the member 2 is such as to position the pin 4 initially in inclined relation to the hole 6 in the last, and that the 75 pin can be forced into the hole only by springing the intermediate portion of the member 2 downwardly toward the insole until the pin is tipped into a position substantially in alignment with the hole. It 80 will thus be seen that after the member 2 has been sprung into clamping position and the pin has entered the hole in the last, the resiliency of the clamping member serves to 85 clamp the pin in the hole through its tendency to tip it, and in this way the clamping member and the pin are held effectively in place. The clamping device, however, may be readily detached from the last when desired by prying it up with the aid of any 90 suitable tool, or in the manner hereinafter described:

In the construction herein shown the clamping member 2 is so shaped as to conform substantially to the lengthwise curvature of the bottom of the last when it is in clamping position. It will be understood, however, that consistently with the objects of the invention the clamping member need not conform with absolute accuracy to the 100 contour of the last, and accordingly it is contemplated that the same size and shape of clamping member may be used for a number of different last sizes, although for wide extremes it will be preferable to provide clamping members of different sizes or shapes. It is further to be understood that in other respects likewise the invention is not restricted to insole-positioning means 105 formed and located precisely as herein illustrated.

It will be seen that by inserting the pin 4 through the hole 10 in the insole and into the hole 6 in the last the forepart of the insole is positioned lengthwise and laterally. 110 and after the clamping device has been applied its pressure on the insole is such as to hold the insole effectively against lateral displacement of its heel end portion. If desired, moreover, for the sake of absolute 115

accuracy, another positioning device may be applied at the heel end of the insole. In the drawings such a device is shown as comprising a short resilient clamping plate 12 provided with a pin 14 to enter a hole formed in the heel end portion of the last in predetermined relation to its contour, the plate 12 having a normal shape such as to cramp the pin 14 in the hole in the last 10 through its resiliency in the same manner as hereinabove described with reference to the forepart and shank clamping device. The insole will be provided with a hole 16 in its heel end to receive the pin 14, and preferably 15 this hole will be formed as a slot extending lengthwise of the insole so as to allow for possible small variations in the length of different insoles or in the accuracy of their conformity to the shank curvature of the last 20 and thus to make it easier to apply the heel end positioning device under varying conditions. It will be understood that the hole or slot in the heel end of the insole will be so located that when it is in alignment with 25 the hole in the last the heel end of the insole will be in the right position.

For the further purpose of positioning the last and its shoe materials relatively to means for operating on said materials, and 30 as herein shown relatively to toe-embracing wipers 18 of a toe lasting machine (Figs. 4 and 5), the clamping member 2 has an outwardly projecting pin 20 thereon formed and arranged to enter a socket 22 in the arm 24 which is fixed on the frame of the machine. The other parts of the machine herein shown need not be described in detail, since they are fully shown and described in the prior application hereinabove 35 mentioned. It will be sufficient to state that the last and shoe are held upwardly against the front end of the arm 24, which serves as a holdown, by means of a toe rest 26, and that the wipers 18 are shaped to conform substantially to the contour of the lateral periphery of the toe and are advanced and closed about the toe under such control 40 that the extent of their closing movement laterally of the shoe bears a definitely predetermined relation to the extent of their advancing movement lengthwise of the shoe. As set forth in said prior application, it is 45 desirable that the shoe be so positioned in relation to the wipers that the wiping edges 50 of the latter will be brought into position substantially to conform to the contour of the toe at that point in their advancing and closing movements when they are about to begin the wiping of the upper inwardly over 55 the insole. To insure such positioning of the shoe, the prior application disclosed a method whereby positioning surfaces are 60 provided on the last and on the machine to cooperate with each other, the positioning 65 surface on the last bearing a definitely pre-

determined relation to the contour of the toe and the positioning surface on the machine bearing the same corresponding relation to the edges of the wipers when the wipers are in position to conform to the contour of the toe. As herein illustrated, positioning surfaces cooperating to position the work in accordance with the method of the prior application are afforded by the periphery of the pin 20 on the last and by the corresponding peripheral wall of the hole or socket 22 in the machine. It will be understood that the holes 6 and 10 in the last and the insole respectively are to be formed in the same predetermined relation to the edge contours of these parts in all shoes of the same size and style, as more fully explained in the prior application, and in order that the pin 20 will similarly be positioned in the same invariable relation to different shoes it is preferable, as herein shown, to mount this pin coaxially with the pin 4. It will thus be seen that each shoe is provided with a fixture which predetermines its relation to the wipers, and that all that the operator has to do in presenting the shoe to the lasting machine is to insert the pin 20 in the socket 22. The shoe is thus mounted so that it may turn about the axis of the pin 20; and in case it should not be pointed in exactly the right direction for the wipers to fit the contour of the toe when they are advanced and closed about the toe, the pressure of the wipers on the shoe will swing the shoe into exactly the right position for the wipers thus to fit the toe, as also more fully set forth in the prior application.

In the use of the invention, the lasts and the insoles having been properly prepared for the application thereto of insole positioning means such as hereinabove described, the operator places an insole on the bottom of its last with its hole 10 in position to register with the hole 6 in the last, and applies thereto the clamping member 2 in the manner hereinbefore explained, pressing this member toward the bottom face of the insole and thereby bending it until the pin 4 is properly seated in the hole in the last. He then swings the insole and the clamping device, if necessary, about the axis of the pin 4 to position the heel end portion of the insole in the right relation to the last, and if the heel end clamping device is utilized, he then applies this device to the insole, pressing it into place in substantially the same manner as the forepart clamping device. The last and the insole are then ready for the upper materials to be assembled thereon and for other manufacturing operations. It will be understood that if the shoe is presented to a pulling-over machine, the shoe rest of such a machine will be so shaped as to provide room for the insole positioning means without interference between these.

parts, or such a machine may have means for engaging the pin 20 to position the shoe. After the pulling-over operation, and it may be also after the side lasting operation as herein illustrated, the shoe is presented to the toe lasting machine, and if this machine is a machine of the type illustrated in Figs. 4 and 5, the pin 20 is inserted in the socket 22 for positioning the shoe in proper relation to the wipers. After the toe lasting operation and prior to the subsequent operations on the shoe, the insole clamping devices are preferably removed, since they are no longer required. This may be done by inserting a suitable tool under the edge of each clamping member so as to withdraw the pin from the hole in the last, or in the case of the forepart clamping means the removal of the clamping device may be conveniently effected by tipping the heel end of the shoe upwardly while the pin 20 is still in the socket 22, thereby counteracting the cramping effect of the clamping member 2 on the pin 4 enough to release the pin from the last.

While the invention is herein illustrated in its application to the manufacture of welt shoes, it will be understood that it is likewise applicable to the manufacture of 30 McKay shoes and shoes of other types.

Having described the invention, what I claim as new and desire to secure by Letters Patent of the United States is:

1. Means for positioning an insole on a last comprising a clamping device portable with the last and having a resilient clamping member for clamping the insole yieldingly on the bottom face of the last, said clamping device being detachable from the last while the last remains in the shoe.

2. Means for positioning an insole on a last comprising a resilient clamping member portable with the last and constructed to apply clamping pressure to the bottom face of the insole substantially midway between the opposite sides of the last.

3. Means for positioning an insole on a last comprising a spring-metal clamp portable with the last and constructed to extend along the bottom face of the insole substantially in the direction of the length of the last in clamping engagement with the insole.

4. Means for positioning an insole on a last comprising a clamping member portable with the last and having means for attaching it to the last, said clamping member being constructed to extend along the forepart of the insole and rearwardly along the shank for holding the shank portion of the insole close to the bottom face of the last.

5. Means for positioning an insole on a last comprising a resilient clamping member for applying clamping pressure to the

bottom face of the insole, and means for 65 attaching said member to the last through a hole in the insole.

6. Means for positioning an insole on a last comprising a resilient clamping member for applying clamping pressure to the 70 bottom face of the insole, and a pin formed to extend through the insole into a hole in the bottom of the last to attach said member to the last.

7. Means for positioning an insole on a 75 last comprising a clamp constructed to extend along the bottom face of the insole at the forepart and the shank, and means for attaching said clamp to the forepart of the last through a hole in the insole. 80

8. Means for positioning an insole on a last comprising a clamp constructed to extend along the bottom face of the insole, and a pin for attaching an end portion of 85 said clamp to the last through a hole in the insole.

9. Means for positioning an insole on a last comprising a resilient insole clamping member portable with the last and formed to extend along the bottom face of the insole, said member having a normal curvature 90 different from that of the corresponding portion of the bottom face of the last to adapt it to be sprung into clamping position, and means for holding said member in 95 clamping position.

10. Means for positioning an insole on a last comprising a resilient clamping member formed to extend along the bottom face of the insole and adapted to be sprung into 100 clamping position, and a pin on said clamping member adapted to extend through the insole into a hole in the bottom of the last and so arranged relatively to the clamping member as to be cramped in said hole by the resiliency of the clamping member to hold 105 said member in place.

11. Means for positioning an insole on a last comprising a spring-metal clamping member formed to extend along the bottom 110 face of the insole and having a normal contour different from that of the corresponding portion of the bottom face of the last to adapt its intermediate portion to be sprung toward the bottom face of the last, and a pin on one end of said clamping member adapted to project through the insole into a hole in the bottom of the last and to be cramped in said hole by the resiliency of 115 said clamping member to hold said member in place.

12. Means for positioning an insole on a last comprising a resilient clamping member formed to extend along the bottom face of the insole to clamp the insole on the last and having a projection adapted to extend through the insole into a socket formed in the bottom of the last, said member being 125

- so shaped as to require it to be subjected to bending stress in forcing said projection into the socket in the last.
13. Means for positioning an insole on a last comprising a spring-metal clamping member formed to extend along the bottom face of the insole at the forepart and the shank and having its rear end portion bent for applying clamping pressure to the shank portion of the insole, and a pin on the other end portion of said member adapted to project through the insole into a socket in the bottom of the last, said member being so shaped between its ends as to require it to be subjected to bending stress in forcing said pin into the socket in the last.
14. The combination of a last having a socket in its bottom portion, a clamping member formed to extend along the forepart and shank of an insole to clamp the insole on the last, and a member formed to project through the insole into said socket in the last to hold said member in place.
15. The combination of a last having a socket in its bottom portion, a resilient clamping member for engaging the bottom face of an insole to hold the insole on the last, and a pin formed to project through a hole in the insole into said socket in the last to hold said member in place.
16. The combination of a last having a socket in the bottom of its forepart, a resilient clamping member formed to extend along the bottom face of an insole at the forepart and also rearwardly along the shank and to apply clamping pressure yieldingly to the shank portion of the insole when subjected to bending stress, and a pin on said clamping member arranged to project through a hole in the insole into said socket in the last and to be crimped in said socket by the resiliency of said member for holding the member in place.
17. The combination of a last having sockets formed in its bottom portion at its toe and heel ends respectively, and insole positioning devices comprising resilient clamping members having pins thereon formed to enter said sockets in the last and arranged to be crimped in said sockets by the resiliency of the clamping members.
18. The combination of a last having sockets formed in its bottom portion at its toe and heel ends respectively, of a resilient clamping member having a pin formed to project through a hole in the insole into the socket in the toe end of the last, said clamping member being shaped to apply clamping pressure yieldingly to the shank portion of the insole, and an additional insole positioning device having a pin formed to project through a hole in the insole into the socket in the heel end of the last for positioning the heel end portion of the insole.
19. In work positioning means, a device constructed to be applied to a last for positioning a loose insole on the last and detachable from the last while the last is in the shoe, said device being portable with the last and having a portion formed to project outwardly at an angle to the bottom face of the insole for engagement with a part of a machine having means for operating on the shoe materials to position the last in predetermined relation to said operating means.
20. In work positioning means, a device for clamping an insole on a last, said device being portable with the last in fixed relation thereto and having a pin arranged to project in substantially perpendicular relation to the bottom face of the insole and formed to enter a socket in a shoe machine to position the last in said machine.
21. In work positioning means, a device for positioning a loose insole on a last comprising a resilient clamping member for engaging the bottom face of the insole, said device having thereon a pin formed to project through a hole in the insole into a socket formed in the bottom of the last and having also a positioning surface coaxial with said pin formed for engagement with a cooperating positioning surface in a machine for operating on the shoe materials for positioning the last in said machine.
22. In work positioning means, a clamp for engaging the bottom face of an insole to clamp the insole on a last, said clamp having projecting therefrom in opposite directions a pair of pins arranged respectively to project through the insole into a socket formed in the bottom of the last and to enter a socket formed in a machine for operating on the shoe materials to position the last in said machine.
23. In work positioning means, a member constructed to be applied to a last in predetermined relation to the contour of the last and to an insole on the bottom of the last before the last is presented to a shoe machine, said member having a projection at the toe end portion of the last formed for engagement with a part of a machine for operating on the shoe materials to position the last in said machine.
24. In work positioning means, a clamp for engaging the bottom face of an insole to clamp the insole on a last, said clamp having thereon a pin arranged to project through the toe end portion of the insole into a socket in the bottom of the last and having also a projection coaxial with said pin formed to enter a socket in a machine for operating on the shoe materials to position the last in said machine.
25. The combination with means for operating on shoe materials on a last, of a device portable with the last, is fixed relation thereto for clamping an insole on the last, said device having a positioning sur-

face thereon in predetermined relation to the contour of the last, and a member provided with a positioning surface in predetermined relation to said means for operating on the 5 shoe materials for engaging the positioning surface on said insole clamping device to position the last relatively to said operating means.

26. The combination with means for operating on shoe materials on a last, of a last 10 having a socket in its bottom portion in predetermined relation to its contour, a work positioning device portable with the last and having a pin to enter said socket through 15 a hole in the insole and also a pin arranged to project outwardly away from the insole, and a member provided with a recess in predetermined relation to said means for operating on the shoe materials to receive 20 said last-named pin for positioning the last relatively to said operating means.

27. The combination with toe-embracing wipers, of a last having a socket in the bottom of its forepart in predetermined relation 25 to its contour, a work positioning device portable with the last and having a pin to enter said socket through a hole in the insole, said device having also a positioning surface for use in positioning the last relatively to the wipers, and a member provided 30 with a positioning surface in predetermined relation to the wipers for engaging the positioning surface on said work positioning device to determine the relation of the last 35 to the wipers.

28. The combination with toe-embracing wipers, of a last having a socket in the bottom of its forepart in predetermined relation to its contour, a device portable with the last 40 for clamping an insole on the last and provided with a pin to enter said socket through a hole in the insole, said device having also a pin projecting outwardly from the insole, and a member provided with a recess in predetermined relation to said wipers to receive 45 said last-named pin for positioning the last relatively to the wipers.

29. The combination with toe-embracing wipers having wiping edges formed substantially to fit the contour of the toe of a shoe 50 when they are closed about the toe, of a work positioning device portable with a last in fixed relation thereto and having a positioning surface thereon in predetermined relation to the contour of the last, and a member provided with a positioning surface in the same relation to the edges of the wipers when the wipers are closed about the toe of the shoe 55 that said first-named positioning surface bears to the lateral periphery of the toe of the shoe for engaging said first-named po- 60

sitioning surface to position the last relatively to the wipers.

30. The combination with toe-embracing wipers having wiping edges formed substantially to fit the contour of the toe of a shoe 65 when they are closed about the toe, of a last having a socket in the bottom of its forepart in predetermined relation to its contour; a work positioning device portable 70 with the last and having a pin to enter said socket through a hole in the insole, said device having also a positioning surface coaxial with said pin, and a member provided with a positioning surface arranged to bear 75 the same relation to the edges of the wipers when the wipers are closed about the toe that said first-named positioning surface bears to the contour of the lateral periphery of the toe for engaging said first-named 80 positioning surface to position the last relatively to the wipers.

31. The combination with toe-embracing wipers having wiping edges formed substantially to fit the contour of the toe of a shoe 85 when they are closed about the toe, of a last having a socket in the bottom of its forepart in predetermined relation to its contour, an insole positioning device portable 90 with the last and having a pin to enter said socket, said device having also a pin projecting outwardly from the insole, and a member having a socket arranged to bear the same relation to the edges of the wipers when the wipers are closed about the toe that said 95 last-named pin bears to the contour of the lateral periphery of the toe to receive said last-named pin for positioning the last relatively to the wipers.

32. Means for positioning an insole on a last comprising a member formed to enter holes previously provided in the insole and the last in predetermined relation to the contour of the insole and of the last respectively, and means for cramping said member in the hole in the last to hold it in place.

33. Means for positioning an insole on a last comprising a pin formed to project through a hole previously provided in the insole in predetermined relation to its edge contour into a hole provided in the bottom of the last in correspondingly predetermined relation to the contour of the edge of the last bottom, and a resilient member arranged to project from said pin over the bottom face of the insole for cramping the pin in the hole in the last.

In testimony whereof I have signed my name to this specification.

ARTHUR F. PYM.
